US00D775976S

(12) **United States Design Patent** (10) **Patent No.:** **US D775,976 S**
(45) **Date of Patent:** ** *Jan. 10, 2017

(54) **CONTROL DEVICE**

(71) Applicant: **Lutron Electronics Co., Inc.**,
Coopersburg, PA (US)

(72) Inventors: **Elliot G. Jacoby**, Glenside, PA (US);
Jason C. Killo, Emmaus, PA (US);
Brad Michael Kreschollek, Bethlehem,
PA (US)

(73) Assignee: **Lutron Electronics Co., Inc.**,
Coopersburg, PA (US)

(*) Notice: This patent is subject to a terminal disclaimer.

(**) Term: **14 Years**

(21) Appl. No.: **29/515,924**

(22) Filed: **Jan. 28, 2015**

(51) LOC (10) Cl. **10-04**

(52) U.S. Cl.

USPC **D10/50**; D13/162

(57) **CLAIM**

We claim the ornamental design for a control device, as
shown and described.

DESCRIPTION

FIG. 1 is a perspective view of a control device showing our
new design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view thereof showing an alternate
environment.

FIG. 8 is a front view thereof.

FIG. 9 is a left side view thereof.

FIG. 10 is a right side view thereof.

FIG. 11 is a top view thereof; and,

FIG. 12 is a bottom view thereof.

The rear views form no part of the design and are omitted.
The portions of the drawings appearing in broken lines are
for environment only and do not form part of the claimed
design.

1 Claim, 8 Drawing Sheets
